UNITED STATES PATENT OFFICE.

EDMUND P. BANNING, JR., OF NEW YORK, N. Y., ASSIGNOR TO "BANNING TRUSS AND BRACE COMPANY," OF SAME PLACE.

IMPROVEMENT IN BACK-BRACES.

Specification forming part of Letters Patent No. 124,473, dated March 12, 1872.

Specification describing a new and Improved Back-Brace invented by EDMUND P. BANNING, Jr., of the city of New York, in the county and State of New York.

Figure 1 represents a back view of my improved back-brace; Fig. 2 is a vertical central section of the same; and Fig. 3, a transverse section on the line C C, Fig. 2.

Similar letters of reference indicate corresponding parts.

This invention relates to a new back-bone brace; and consists in a new arrangement of parts, more particularly in the method of the adjustable application of an up-and-down adjustable and partly flexible fulcrum for the same, as hereinafter more fully described.

A in the drawing represents the back-bone brace, made of a flat spring of proper length, width, and thickness, and sufficiently powerful for the purposes to which it is to be applied. The spring is inclosed in a sheath or covering, *a*, of suitable fabric. Its upper end carries a pivoted transverse piece or plate, *B*, to the ends of which the upper parts of the shoulder-straps *C C* are secured. The lower ends of these shoulder-straps are secured by links *b b*, or otherwise, to a short strap, *d*, projecting from the sheath *a*, as shown, or directly to said sheath. The straps *C* contain buckles, *e*, or equivalent devices, for being lengthened or shortened, according to the figure of the patient, the upper plates *B* being pivoted allows free side motion to the body without affecting the position of the spring *A*. To the lower end of the spring *A* is pivoted another transverse piece or plate, *D*, to which the body-

belt *E* is connected. The pivoting of the piece *D* offers the same advantages as that of *B*. The fulcrum of the brace is formed by two small metallic pads or plates, *F F*, which are, by more or less flexible joints *ff*, secured to a transverse bar, *g*, that slides on the spring *A*. By means of a plate, *h*, secured or bolted to *g*, the latter is transformed into a sleeve that embraces the spring *A*, and can be vertically adjusted thereon. The pads *F* can therefore be set up or down at will to fit the small of the back of the patient.

I am aware that the dorsal pads have been adjustably secured to the central upright spring, and I therefore do not claim this of itself.

Having thus described my invention, I claim as new, and desire to secure by Letters Patent—

1. The combination of back-piece *B* curved to pass over shoulder-blades and concaved to throw lever close into back, and adjustable, flexible straps secured thereto and to the central spring *A*, the spring back-bone brace *A*, and the pivoted sacral or body-belt plate *D*, when constructed and arranged as and for the purpose set forth.

2. The method of fastening the dorsal springs or pads *F* to the dorsal lever *A*, by means of double plates embracing the upright spring *A* and two set-screws applied at the ends thereof, as and for the purpose described.
